CATHODE-RAY TRANSLATING DEVICE

Herbert Ziebolz, Chicago, Ill., assignor, by mesne assignments, to Electronbeam, Ltd., Chicago, Ill., a partnership of Illinois

Application March 13, 1943, Serial No. 479,153

12 Claims. (Cl. 250—151)

The invention relates to an electronic translating device of the cathode-ray tube type for relaying, amplifying, converting, transforming or otherwise translating electrical signals or signals of any nature which may be converted by known means into electric signals. The invention is useful in translating signals representing physical, chemical or other conditions, such as chemical reactions, heat, sound, light, mechanical motion or displacement which may be converted into electric signals by such means as thermocouples, microphones, light sensitive cells, or other devices.

The present invention is related to the invention disclosed in the specification of my pending application Serial No. 417,871, filed November 4, 1941, issued as Patent 2,314,302, March 16, 1943, and the arrangements described in the present application are modifications of the invention disclosed in the said specification.

In the apparatus described in my earlier application, the electron stream or beam of a cathode-ray tube is deflected by suitable deflecting means to vary the number of electrons intercepted by electron receiving means or an anode, the deflecting means being energized in accordance with signals to be translated. A second deflecting means is provided to act upon the electron stream in opposition to the first deflecting means, and the second deflecting means is energized in accordance with variations in the number of electrons acting upon the electron receiving means or anode, the arrangement being such that the stream is deflected to establish a state of equilibrium between the two deflecting means.

The apparatus according to the present invention operates by varying the focusing of the electron beam and includes a cathode-ray or vacuum type tube in which an electron stream or beam is produced, means for focusing the beam upon an electron intercepting means, means for varying the focusing of the beam in accordance with signals to be translated, and a counter-focusing means energized from the output (electron intercepting means) and acting upon the electron beam in opposition to the first focusing means, thereby producing variation in the number of electrons intercepted by the electron receiving means, the arrangement being such that the beam is focused to establish a state of equilibrium between the opposed focusing effects.

The translating functions are performed with a minimum of distortion due to any change in

the characteristics of the means or of the electronic device, and without reflecting any variation from the controlled means back into the signal source.

5 The invention provides for amplifying or repeating signals so that the output signals have a linear relation to the input signals. Also, an electronic device of this character can be employed as a direct current amplifier.

10 Other aims and advantages of the invention will appear in the specification, when considered in connection with the accompanying drawings, wherein:

Figure 1 is a circuit diagram showing one form 15 of translating device according to the invention;

Figures 1a, 1b and 1c are detail views in side and front elevation of the cathode beam interceptor discs under different conditions of operation;

20 Figures 2, 3, 4 and 5 are circuit diagrams similar to Figure 1 of further translating devices embodying the present invention.

In the arrangement shown in Figure 1, there 25 is diagrammatically represented a cathode-ray tube consisting of an insulating envelope 20. The internal construction of the cathode-ray tube may be of any suitable and well known type, but for the purpose of illustration, the tube has 30 a source of electrons represented by a heater or filament 21 for heating an electron emitting cathode 22. The electrons emitted by cathode 22 are accelerated and focused into an electron beam of suitable shape and are directed along the axis of the tube by means of a system of 35 accelerating and concentrating electrodes comprising a grid or control electrode 20a, a first anode 23 and a second anode 23a mounted in the tube. The elements are maintained at proper potentials with respect to the cathode 22 by means of a suitable source of potential, represented by the battery 24 and potentiometer 24a. The electron beam established within the tube is indicated by dotted lines 25.

45 Suitable electron receiving means, represented by the discs 26 and 27 of different diameter are axially spaced from each other within the tube to receive electrons from the beam 25. The discs 26 and 27 are connected to suitable coupling resistances 28 and 29 and are shown as being connected to receive a positive potential from the battery 24 relatively to the cathode 22. Moreover, it is not essential that resistances 28 and 29 be connected to the battery 24, but they 50 may be connected to ground. A load or output

circuit or any other device 31 utilizing load current or potential is connected directly across the leads to discs 26 and 27. Two pairs of deflection plates 100 and 101, the pair 100 acting at right angles to the pair 101, are also mounted in the cathode ray tube and are connected to the battery or other source of potential through suitable adjusting resistances, as shown, for the purpose of centering the beam on discs 26 and 27 or for setting the beam to any other desired initial position.

The electron beam 25 may be initially concentrated or focused on the discs 26 and 27 to give an equal electron interception on each disc, as indicated in Figure 1b. This may be accomplished by adjusting the potentials applied to anodes 23 and 23a from potentiometer 24a until there is no difference of potential between plates 26 and 27. The beam is variably contracted or expanded to different cross-sectional areas by superimposing on anode 23 a variable potential derived from a suitable source of signal or input current 33, whereby the beam is contracted or expanded depending upon the increase or decrease of the input current or potential drop across the input resistor 33a.

Variation in cross-sectional area of the beam 25 in accordance with signals from the source 33 causes corresponding variations in the relative number of electrons focused and impinging upon plates 26 and 27, as will be readily understood from Figures 1a, 1b, 1c, thereby causing discs 26 and 27 to vary in potential in response to the signals from source 33. The difference in potential between the plates supplies the load or output circuit 31 with current or voltage which varies in accordance with the signals supplied from source 33.

A counter-focusing magnetic field is established axially of the beam 25 by means of a magnetic coil 34 which is shown as being energized by current derived from the potential variations existing between discs 26 and 27. The coil 34 is so connected to the output circuit that its field tends to focus the beam 25, or to vary its cross-sectional area, in an opposite direction from the action of anode 23. The field of coil 34 produces a concentrating action for either direction of current through the coil, so it is desirable to provide for an initial or biasing current in the coil which is varied above and below its normal value in accordance with the input signals. The normal biasing current for coil 34 may be derived from battery 24 by connecting coil 34 to the output circuit by means of variable contacts on resistors 28 and 29 as shown in Figure 1, or it may be supplied from a separate source as in Figures 2 to 4.

The operation of the arrangement shown in Figure 1 is believed to be clear from the foregoing description. It is assumed that the field established by the plates 100, 101 centers the beam on plates 26 and 27 and that the initial focus of the beam provides equal distribution between the disc 26 and the disc 27 as shown in Figure 1b whereby with zero input, no potential difference is established between discs 26 and 27. However, a normal biasing current flows in coil 34, exerting a certain concentrating action on the beam.

A signal or input voltage increases or decreases the voltage applied to anode 23, thereby varying the cross-sectional area of the beam at plates 26 and 27. An increase in signal strength relatively to the initial or datum setting produces concentration of the beam, which condition is shown

in Figure 1a, in which all the electrons impinge on the smaller disc 26. A decrease in signal strength will cause dispersal or increase in cross-sectional area of the beam whereby more electrons will impinge on the disc 27 than on the disc 26, a condition shown in Figure 1c. The resulting potential difference between electrodes 26 and 27 changes the currents flowing in resistors 28 and 29 and thereby changes the current in coil 34 in a direction such as to establish a counter-focusing action which tends to focus the beam in the opposite direction, that is it tends to restore the initial distribution of the electrons between the discs 26, 27. In case a steady signal voltage is supplied to anode 23, the beam 25 will assume a position in which the focusing and counter-focusing actions are in a state of equilibrium and, under this condition, the potential difference existing between discs 26 and 27 will be directly proportional to the applied signal.

Preferably, the amount of counter-focusing required to produce the maximum difference in potential is produced by a relatively small unbalance between the actions of the anode 23 and of the coil 34. For example, the amount of unbalance may be only 1%.

For the reasons explained in the specification of my prior patent application No. 417,871 which reasons apply equally to the present instances, there will be a substantially linear relationship between the input signal voltage and the voltage produced across the load, and this relation is not substantially affected by changes in the operating characteristics of the cathode-ray tube.

The arrangement shown in Figure 2 is generally similar to that of Figure 1 and operates on the same principle of variable focusing of the beam on a pair of axially aligned discs of different diameters. In this modification, however, the input is not connected to anode 23 but the anodes 23, 23a are directly connected to points of suitable potential on potentiometer 24a, the potentials being adjusted to values which will give the condition of Figure 1b for zero or datum strength of input signal. The input device 33 is connected to the focusing coil 34 whereby an input signal will focus the beam in the direction of Figure 1a or that of Figure 1c according to whether it is an increase or a decrease relatively to the zero or datum for which the tube is initially adjusted. The normal biasing current for coil 34 is supplied from a suitable source represented by battery 35 and potentiometer 35a. The potential difference across discs 26, 27 is fed back through an amplifier 103 to the focusing coil 34 in such a manner as to oppose the action of the input signal therein. The amplification is applied to a potentiometer 104 so connected that the variable part of the amplified voltage is in opposition to the input voltage. The load circuit is connected to the output of amplifier 103.

The initial focus of the beam in Figures 1 and 2 may be controlled or set by adjusting the value of the biasing current in coil 34, as well as by adjusting the potentials applied to anodes 23 and 23a.

Figure 3 illustrates a third modification. In this arrangement a single accelerating anode 23 is employed which may or may not be used for controlling the initial focus of the beam. The initial focus of the beam may be controlled by the adjustable biasing current supplied to coil 34 from source 35. A second magnetizing coil 32 arranged concentric with the tube and substantially co-extensive with coil 34 is energized by the signal-

ling current from the source 33 and serves to vary the focusing field acting on the beam. As in Figure 2, a counterbalancing voltage is supplied to the circuit of magnetizing coil 34 from potentiometer 104 connected across the output circuit.

The operation of Figure 3 is believed to be clear. The incoming signal disturbs the balance between the electrons received by the two electrodes 26 and 27 and produces a potential variation across the output circuit which is impressed back upon the circuit to coil 34 in a direction tending to restore the condition of the focusing field acting on the beam. The normal biasing current supplied to coil 34 from source 35 should be sufficiently large so that the incoming signal does not reverse the focusing field acting on the electron beam.

It may be noted that Figure 3 discloses an alternative arrangement of the electrodes 26 and 27 in that electrode 26 is formed as an apertured plate positioned in front of electrode 27. This arrangement is equivalent to the arrangements shown in Figures 1 and 2 and the two arrangements may be used interchangeably. An amplifier like that shown in Figure 2 may be used in Figure 3 if desired.

In all of the modifications shown in Figures 1 to 3, it will be understood that when an input signal is applied to the system, the focusing of the electron beam 25 is influenced, resulting, according to the sign of the signal relatively to an initial or zero value, in a more concentrated spot of electron interception (Figure 1a) or in a larger spot (Figure 1c). In either case, one or the other disc 26, 27 receives more electrons than the other whereby a potential difference is set up between the discs. This potential difference, or a part of it, is applied to a feedback circuit which influences the focusing of the beam in a direction opposite to the influence of the signal.

In the modification shown in Figure 4 the electrode arrangement is the same as that shown in Figures 1 and 2 except that only one accelerating anode is employed, and the input signal is applied to vary the potential on control grid 20a. The initial focus of the beam is controlled by adjusting the normal biasing current supplied to coil 34 from source 35. The circuit of coil 34 also includes a variable portion of coupling resistance 28, and the arrangement is such that the potential drop across the included portion of resistance 28 opposes the potential supplied from source 35. It will be understood, however, that coil 34 may be energized by connections like those shown in Figure 3. The load circuit may be connected directly across electrodes 26 and 27 as shown at 31, or one terminal of the circuit may be connected directly to one of the electrode leads and the other terminal connected to a variable tap on potentiometer 24a to counterbalance the normal potential drop across resistance 29, as shown at 31a. It will be understood that the load circuit connection 31a in Figure 4 may be used in any of the other figures.

In the operation of Figure 4, the normal biasing current in coil 34 is adjusted to establish a predetermined relation between the electrons received by plates 26 and 27. The incoming signal does not affect the focus of the beam but varies the intensity of the beam and causes corresponding variations in the potential drop across coupling resistances 28 and 29. The change in potential drop across resistance 28 is in a direction to vary the biasing current in coil 34 and thereby vary the focus of the beam in a manner to counteract the

effect of the grid 20 upon the amount of electrons received by plate 26. In other words, if the incoming signal increases the intensity of the beam, the potential drop across resistance 28 increases, thereby resulting in less current through coil 34 which causes the beam to spread and reduces the number of electrons received by electrode 26. By energizing coil 34 from the potential drop across a variable portion of resistance 29, the biasing source 35-35a may be omitted.

Figure 5 illustrates an arrangement reversed from that of Figure 1, that is, the input signal is connected to energize coil 34, while the counter-focusing effect supplied from the output circuit is applied to the anode 23. In this arrangement, a suitable separator circuit C is interposed between the circuit of anode 23 and the potentiometer 104 connected to the output circuit. This separator circuit is provided to prevent short-circuiting of part of the anode battery, and it may be formed of any suitable D. C. amplifier circuit of well known construction. It could be formed of another electron beam tube circuit having a coil input.

If no source of biasing current is connected in series with coil 34 in Figure 5, both positive and negative pulses of the signal source 33 will exert a concentrating action on the electron beam, since a signal of either polarity has a converging effect on the beam. Accordingly, the potential variations produced in the output circuit will all be of one polarity, and the resulting output current will correspond to a pulsating direct current having a principal alternating component of a frequency equal to double the frequency of the input signal. Part of the output taken from potentiometer 104 is supplied through separator circuit C to vary the potential of anode 23 which exerts a diverging influence on the beam. Since the polarity supplied to anode 23 from the output circuit is always the same, the feedback action on anode 23 will always be divergent, and tends to counteract the converging effect of the input coil 34. The circuit arrangement of Figure 5 may be employed as a full wave rectifier where the input signal is an alternating current. Also, by providing a suitable smoothing filter in the output circuit, the circuit of Figure 5 may be used to derive a direct current from an alternating current signal, the direct current being proportional to the amplitude of the alternating current signal. It is also obvious that the circuit of Figure 5 may be used as a frequency doubler, since the output circuit includes a strong double frequency component.

The focusing coil or coils 32, 34 in the several arrangements are shown as extending over a substantial length of the cathode ray tube, but short coils may be used if desired. Purely electrostatic focusing means may be used for the initial focusing of the beam, and for the counter-focusing. In Figure 3, the initial biasing current may be supplied to coil 32 instead of to coil 34, if desired.

The discs 26, 27 may be of any desired shape and means may be provided to avoid undesired influence of secondary electrons.

It will be obvious to those skilled in the art that the input signal may be derived from any condition or conditions which can be translated into electromagnetic or electrostatic fields which control the focus of the electron beam. Likewise, the input signal may be set or adjusted or it may be varied and the output signal, which may be of a different magnitude or character, can be maintained proportional to the input signal.

Obviously, the present invention is not restricted to the particular embodiments thereof herein shown and described.

What I claim is:

1. Electronic translating apparatus comprising a cathode-ray tube, means for focusing the electron beam thereof, electron receiving means positioned to receive a variable portion of the electrons of said beam dependent on variations in focus thereof, input means acting on said cross-sectional area means to vary the focusing of the cathode beam from a datum cross-sectional area, counter-focusing means arranged to vary the cross-sectional area of the cathode beam in opposition to said focusing means, and means for energizing said counter-focusing means in accordance with variations in electrons received by said electron receiving means.

2. Electronic translating apparatus comprising a cathode-ray tube, means for focusing the electron beam thereof, a pair of overlapping concentric discs of different sizes arranged in the path of said beam for intercepting different concentric portions thereof, input means arranged to vary the focusing of the cathode beam from a datum differential of electron interception between said discs, counter-focusing means arranged to vary the focusing of the cathode beam in opposition to said focusing means, and means for energizing said counter-focusing means in accordance with the difference in electron interception of said discs.

3. Electronic translating apparatus comprising a cathode-ray tube, input means including an anode system arranged to vary the focusing of the cathode beam from a datum cross-sectional area, electron receiving means positioned to receive a variable portion of the electrons of said beam dependent on variations in focus thereof, counter-focusing means including a magneto-static coil developing a field with its lines extending in the path of the electron beam and arranged to vary the focusing of the cathode beam in opposition to said focusing means, and means for energizing said magneto-static coil in accordance with the electrons received by said electron receiving means.

4. Electronic translating apparatus comprising a cathode-ray tube, an electrode for receiving at least a portion of the electrons of the cathode beam, means controlled by input signals for varying the number of electrons received by said electrode, focusing means acting on the cathode beam for varying the concentration of the beam on said electrode, and means responsive to the variation in electrons received by said electrode for energizing said focusing means to vary the concentration of said beam in a direction tending to oppose the action of the input means in varying the number of electrons received by said electrode.

5. Electronic translating apparatus according to claim 4 wherein said focusing means comprises a coil for establishing a magnetic field extending along the path of said beam, and including means for supplying a normal biasing current to said coil.

6. Electronic translating apparatus comprising a cathode-ray tube, focusing means tending to spread the beam of said tube, second focusing means tending to concentrate said beam, electron receiving means positioned to receive a variable portion of the electrons of said beam dependent on variations in focus thereof, input means for varying the effect of one of said focusing

means, and means responsive to variations in the electrons received by said electron receiving means for varying the effect of the other of said focusing means in opposition to the variation produced by said input means.

7. Electronic translating apparatus comprising a cathode-ray tube, an anode of fixed potential focusing the electron beam thereof to a predetermined cross-sectional area, electron receiving means positioned to receive a variable portion of the electrons of said beam dependent on variations in the focus thereof, a magneto-static coil arranged to produce a field of force extending in the path of the electron beam to vary the focusing thereof, input means arranged to vary the action of said magneto-static coil in one direction, and output means influenced by said electron receiving means and arranged to vary the focusing of the electron beam by said coil in the opposite direction.

8. Electronic translating apparatus according to claim 7 including amplifying means between the electron receiving means and the magneto-static coil.

9. Electronic translating apparatus comprising a cathode-ray tube, an anode of fixed potential for focusing the electron beam thereof to a predetermined cross-sectional area, electron receiving means positioned to receive a variable portion of the electrons of said beam dependent on variations of the focus thereof, a magneto-static coil arranged to develop a field of force with its lines extending along the path of the electron beam of said tube to vary the focusing thereof, input means arranged to vary the field of said magneto-static coil, a second magneto-static coil arranged to produce a similar field of force, and means for energizing said second coil in accordance with variations in electrons received by said receiving means and in a direction to establish a field in opposition to the field of said first coil.

10. Electronic translating apparatus according to claim 1 and including beam deflecting means operable in two different planes for adjusting the initial beam position of said beam.

11. Electronic translating apparatus comprising a cathode ray tube including means for producing an electron beam, an anode for controlling the focus of said electron beam, electron receiving means positioned to receive a variable portion of the electrons of said beam dependent on variations in the focus thereof, input means including a magnetic coil arranged to produce a variable magnetic field along the path of said electron beam to vary the focusing thereof, an output circuit controlled by said electron receiving means, and a connection from said output circuit to said focusing anode to vary the focusing of the electron beam in opposition to the action of said magnetic coil.

12. Electronic translating apparatus comprising a cathode-ray tube having the electron beam thereof focused to a predetermined cross-sectional area, electron receiving means positioned to receive a variable portion of the electrons of said beam dependent on variations in the cross-sectional area thereof, means for producing a magnetic field extending in the path of the electron beam to vary the focusing thereof, input means arranged to vary the intensity of said field in one direction, and output means influenced by said electron receiving means and arranged to vary the intensity of said field in the opposite direction.

CERTIFICATE OF CORRECTION.

Patent No. 2,358,902.

September 26, 1944.

HERBERT ZIEBOLZ.

It is hereby certified that error appears in the printed specification of the above numbered patent requiring correction as follows: Page 4, first column, lines 10 and 11, for "cross-sectional area" read --focusing--; line 11, for "focusing" read --cross-sectional area--; and that the said Letters Patent should be read with this correction therein that the same may conform to the record of the case in the Patent Office.

Signed and sealed this 5th day of December, A. D. 1944.

Leslie Frazer
